SWITCHING MECHANISM

Daniel G. Taylor and Albert L. Judson, Minneapolis, Minn., assignors to Minneapolis-Honeywell Regulator Company, Minneapolis, Minn., a corporation of Delaware

Application May 7, 1937, Serial No. 141,303

11 Claims. (Cl. 200—83)

This invention relates to switching mechanism and more particularly to a type of switching mechanism adapted to be utilized to control a condition controlling agency such as a refrigerator or heater or analogous mechanism in response to the value of a condition to be controlled.

One object of this invention is the provision of an improved mechanism of the character above mentioned wherein a novel leverage arrangement is utilized to provide a multiplication of a relatively small movement of a condition responsive member to a relatively great movement of contact members associated therewith.

An additional object is the provision in a mechanism embodying a spring opposed to a condition responsive member of means to compensate the increased tension of the spring upon movement of the mechanism counter to the bias thereof in combination with such a leverage arrangement as mentioned in the preceding paragraph.

A still further object is the provision in combination with such a means for compensating for the increased tension or compression of the spring and a leverage arrangement as above mentioned of means to insure a relatively rapid movement of the contacts toward and away from each other in such manner as to preclude to a substantial extent arcing between the contacts.

An additional object is the provision in combination with the mechanism previously mentioned of means whereby the operating differential of the instrument may be readily and simply varied. It should be here pointed out that in instruments of the character to be hereinafter described it is frequently desirable that provision be made whereby the condition value at which the contacts, illustratively, close be varied with respect to the condition value at which the contacts open and that such adjustment be so arranged that either value may be varied independently of the other.

An additional object of this invention is the provision of such differential adjustment means in combination with a leverage arrangement as above mentioned and means for compensating for the increasing compression or tension of a spring as previously mentioned.

An additional and more specific object is the provision of a switching mechanism which will be relatively simple to manufacture, sturdy and durable in construction, and reliable and efficient in operation.

Further objects will in part be obvious and in part pointed out hereinafter.

The invention accordingly consists in the combination of elements, arrangement of parts, and features of construction, all as will be more fully pointed out hereinafter and shown in the accompanying drawing wherein:

Figure 1 is an elevational view of one form of structure embodying the inventive concept,

Figure 2 is a view similar to Figure 1 showing certain parts in a different position of adjustment, certain other parts being broken away to more clearly show certain structural details, 5

Figure 3 is a sectional view taken along the line 3—3 of Figure 1 as viewed from the top,

Figure 4 is a sectional view taken substantially along the line 4—4 of Figure 1 as viewed from the left, 10

Figure 5 is a sectional view taken along the line 5—5 of Figure 1 as viewed from the left, and

Figure 6 is a perspective view showing certain details of construction. 15

Similar reference characters refer to similar parts throughout the several views of the drawing.

Having reference now to Figures 1 and 2, there is generally indicated at 10 a casing having an 20 aperture 11 in the base thereof. Secured to the base of casing 10 is a plate 12 having an internally threaded flange 13 adapted to project through aperture 11. Secured in turn to plate 12 is a housing 14 having rigidly affixed thereto a 25 boss 15 provided with an aperture 16 therethrough. A capillary tube 17 engages boss 15 in fluid tight relationship and extends to a suitable volatile fluid filled bulb (not shown).

A bellows 18 is contained within housing 14, its 30 upper end secured to a flange 19 secured peripherally to the walls of housing 14. The lower end of bellows 18 is secured to a movable plate 20 to the inner or upper side of which is rigidly secured an operating rod or plunger 21. A threaded nut 22 engages the inner threaded portion of flange 13 and is provided with an aperture 23 through which operating rod 21 projects into casing 10. A spring 24 is positioned between a recess 25, formed in nut 22, and plate 20 and serves 35 normally to bias plate 20 and hence operating rod 21 downwardly as viewed in Figures 1 and 2 in opposition to the pressure of the volatile fluid admitted to housing 14 through aperture 16. Thus it will be understood that a change in the 40 condition value in the space containing the bulb previously mentioned will cause the fluid therein to volatilize or liquefy in accordance with the direction of the change causing a relative upward or downward movement of plate 20 occasioned by compression or expansion of bellows 18 45 and a corresponding movement of operating rod 21.

Nut 22 is provided on its upper surface with a recess 27 in which is seated one end of a spring 50 28, the other end of which abuts a collar 29 rigidly secured to operating rod 21 in any desired manner. Thus it will be seen that spring 28 biases operating rod 21 in an upward direction against the pressure of spring 24. The purpose of spring 55 60

28 is to permit the instrument to operate under those conditions wherein a vacuum or sub-atmospheric pressure exists in housing 14. It will be understood of course the spring 24 is of greater strength than spring 28.

Operating rod 21 terminates in a pointed tip 35 positioned to engage a cup 36 carried by boss 32 held in place on a lever 37 as by a spring collar 33. Lever 37 is pivoted on a knife edge 38, 10 knife edge 38 engaging a pair of grooves 39 in lever 37 (see Figure 3). The end of lever 37 opposite cup 36 carries a boss 40 which serves as a seat for one end of a coil spring 41, the other end of which is seated upon a boss 42 secured to the base of casing 10. A second lever is generally indicated at 43 and comprises a pair of extending portions 44 connected at their extremities as by a pin 45, and a relatively wide portion 46 (see Figure 3). Portion 46 is provided with 15 an aperture 34 therethrough, through which boss 32 may project, thus permitting levers 37 and 43 to lie in relatively close proximity to each other. Lever 43 is mounted adjacent lever 37 and pivotally secured thereto as by a pin 48 extending 20 through suitable apertures in extending portions 44 and upwardly turned lugs 49 which latter form an integral part of lever 37.

A pair of bracket members 50 are suitably secured to the side wall of casing 10 and formed 30 to provide a pair of parallel extending surfaces 51, each of which is provided with a threaded aperture, and positioned on opposite sides of pin 45. Screws 52 provided with enlarged heads 53 extend through the above mentioned threaded apertures and are positioned for abutment with pin 45 for a purpose to be hereinafter described. Thus it will be seen that upon upward movement of operating rod 21, lever 37 is rotated 40 about knife edge 38 against the pressure of spring 41. Simultaneously lever 43 is moved through pivot 48 upwardly about pin 45, which through its abutment with the upper of enlarged heads 53 serves as a fulcrum for lever 43.

A pair of opposed brackets 55 and 56 are secured to the base of casing 10 in any desired manner as by screws or rivets 57 and extend upwardly on opposite sides of levers 37 and 43 at that end thereof adjacent spring 41. A connecting portion 58 serves as a support for knife edge 38 which is secured thereto by screws or rivets 59.

A member 60 is pivotally secured as by pivots 61 and 62 to supporting members 55 and 56 respectively (see Figure 3). A slot 63 formed in member 60 is positioned for engagement with a pin 65 carried by the distal end of an extending member 66 comprising an integral portion of lever 43. Member 60 has at its upper extremity an inwardly curved portion 70 terminating in a 60 hook shaped portion 71 which engages one end of a link 72 provided at its extremities with extending lugs 73 to prevent dislodgement of the same from its engagement with hook 71 (see Figure 5). The opposite end of link 72, also provided with lugs 73, engages a corresponding but oppositely formed hook 75 carried by a member 76 pivoted as by a pivot pin 77 to extending portions of supporting members 55 and 56.

Member 76 carries an upwardly extending portion 78 to which is secured an insulating block 79 carrying a pair of contacts 80. A spring 81 secured to an extending post 82 provides a strain release to maintain a definite contact pressure and to preclude damage to or bending of contacts 80 and their associated contact carrying

members upon engagement thereof with opposed stationary contacts 83, only one of which is disclosed in Figures 1 and 2 of the drawing. Contacts 83 are each in electrical association with one of a pair of terminals 84 mounted in an insulating block 85 secured to the upper wall of casing 10. Suitable wires may be secured to terminals 84 and lead to any desired mechanism which it is desired to control in response to the opening or closing of contacts 80 and 83.

Member 76 is also provided with a substantially horizontally extending portion 90 formed with a right angled portion 91 through which is passed an aperture 92, (see Figure 6) adapted to have secured thereto an end of a spring 94, (see Figures 1 and 2), the other end of which is secured to a bracket 95 which is in turn rigidly secured to the base of casing 10 in any desired manner.

Thus it will be seen that upon movement of lever 43 in the manner previously described such movement is transmitted through the pin 65 and slot 63 to member 60 whence it is in turn transmitted through link 72 to member 76 and hence to opening or closing movement of contacts 80 with respect to their opposed contacts 83.

Supporting member 55 is provided with an inwardly turned portion 97 having a threaded aperture therethrough in which is positioned a screw 98 having an enlarged head 99, head 99 being so positioned as to serve as a stop to limit the travel of member 60 in such manner that when contacts 80 engage their opposed contacts 83, link 72 and knife edge 38 are in substantially vertical alignment for a purpose to be herein- 30 after pointed out.

Assume the parts in the position shown in Figure 2 the spring 24, the spring 41 and the spring 94 are all urging the plunger 21 downwardly and the forces exerted by the springs are additive. The springs 24 and 41 act directly to move the plunger downwardly while the spring 94 acts through the link 72. The force exerted by the spring 94 is transmitted through a lever arm the length or radius of which is equal to the right angle distance between the pivot 61 and the prolongation of link 72. The spring 94 also acts to maintain the contacts 80 and 83 separated. Assume now that the pressure within the casing 14 increases to move the plunger 21 upwardly, the lever 37 is rotated in a counter-clockwise direction about its pivot 38 and as a result the lever 44 is rotated in a clockwise direction about its pivot 45. Clockwise movement of the lever 44 causes clockwise movement of the lever 60 about its pivot 61. This movement of the lever 60 causes right hand movement of the upper end of the link 72 and also downward movement of the link 72 and hook 75. Downward movement of the hook 75 in turn causes counter-clockwise rotation of the lever 78 to move the contacts 80 into engagement with the stationary contacts 83. These contacts engage before the lever 60 engages its stop 99 and further movement of the lever 60 into engagement with the stop 99 increases the contact pressure of the contacts, this mode of operation being afforded by the spring 81.

It will be noted that as the link 72 is moved to the right the mechanical advantage of the lever 70 70 60 over the contact lever 78 decreases and is at a minimum when the link 72 is in a vertical position. This means that at the moment of making and breaking the contacts there is a maximum of force available for closing the contacts 75

with a good firm pressure and for breaking them apart if they should stick. After the contacts have been separated the rate of movement of the movable contact increases, due to the increase in the mechanical advantage of lever 60 over lever 78 through link 72, and the force decreases, it being noted that after the contacts have once been separated not much force is needed.

10 As the plunger 21 is moved upwardly to close the contacts 80 and 83 in the manner pointed out above the compression or tension in the springs 24 and 41 as well as in bellows 18 is increased and therefore they afford a greater resistance to movement of the plunger 21. However, as the upper end of the link 72 moves toward the right as a result of upward movement of plunger 21 the leverage arm which transmits the retarding force of the spring 94 is decreased so that when the link 72 reaches the position shown in Figure 1 where the ends of the link 72 are in alignment with the pivot 61, the retarding force of the spring 94 becomes zero. It follows then that as the resistance of the springs 24, 41 and bellows 18 increases, the retarding effect of the spring 94 decreases and if the retarding effect of the spring 94 is decreased at the same rate that the retarding effect of the springs 24, 41, and bellows 18 is increased, the increase in the retarding effect of the springs 24, 41, and bellows 18 is entirely compensated.

By reason of the above arrangement as soon as the plunger 21 is started upwardly upon an increase in pressure in the chamber 14, this pressure will continue upward movement of the plunger 21 whereupon the contacts 80 move immediately and freely into engagement with the contacts 83. If the pivot pin 45 for the lever 44 is held rigid the operating differential of the instrument will be very small, if not practically zero, by reason of the spring rate compensation feature so that the contacts 80 and 83 will be made and broken for extremely small pressure differentials affecting the bellows 18.

45 In order to widen the pressure differential and provide an adjustment of the pressure differential, means are provided for allowing a limited movement of the pivot pin 45. Assume in Figure 2 that the top stop 53 is moved upwardly so as to allow a predetermined amount of movement of the pivot pin 45 and that the pivot pin 45 is engaging the bottom stop 53. Upon a pressure increase within the chamber 14 the plunger 21 is moved upwardly to cause counter-clockwise rotation of the lever 37 which in turn causes counter-clockwise rotation of the lever 44 about the pivot 65 since the pivot 65 is held relatively stationary by the spring 94. When the lever 44 has rotated sufficiently far in the counter-clockwise direction to cause the pin 45 to engage the upper stop 53, the lever 44 will move in a clockwise direction about the pivot pin 45 to cause counter-clockwise movement of the lever 60 and the contacts 80 and 83 will thereupon be closed in the manner pointed out above. By reason of the above arrangement the spring rate compensation afforded by the spring 94 and the link 72 will not come into effect until such time as the pivot pin 45 engages the top stop and therefore 70 the plunger 21 must move upwardly against the increasing retarding action of the springs 24 and 41 until the pin 45 engages the top stop 53. When, however, the pin 45 engages the top stop 53 the spring rate compensation feature comes 75 into operation and causes immediate and free

movement of the contacts 80 into engagement with the contacts 83.

With the parts in the position shown in Figure 1 a decrease in pressure in the casing 14 allows downward movement of the plunger 21 which in turn causes clockwise rotation of the lever 37. Clockwise rotation of the lever 37 causes the lever 44 to rotate in a clockwise direction about the relatively stationary pivot pin 65 until such time as the pivot pin 45 shall engage the lower stop 53. Immediate downward movement of pin 65 is prevented by allowing link 72 to pass slightly over center as it moves lever 78 into contact closing position. When pivot pin 45 engages lower stop 53 the lever 44 is rotated in a counter-clockwise direction about the pivot pin 45 to cause counter-clockwise rotation of the lever 60 whereupon the contacts 80 and 83 are separated. From this it is seen that upon a decrease in pressure in the chamber 14 the pivot pin 45 is moved from engagement with the upper stop 53 to the lower stop 53 before any movement of the levers 60 and 78 is had.

It follows then that by adjusting the upper stop 53 the pressure value at which the contacts 80 and 83 are caused to close is varied and likewise by adjusting the lower stop 53 the pressure value at which the contacts 80 and 83 are opened is varied. By independently adjusting these stops 53 the cut-in point and the cut-out point of the switching mechanism may be adjusted independently of each other. The greater the distance between the two stops 53 the wider the operating differential of the switching mechanism becomes. By adjusting the nut 22 the tension or compression of the spring 24 may be varied to adjust the pressure setting of the instrument.

Although for purposes of illustration one form of this invention has been disclosed, other forms thereof may become apparent to those skilled in the art upon reference to this specification and therefore this invention is to be limited only by the scope of the appended claims and prior art.

We claim as our invention:

1. A condition responsive switch comprising, a switch mechanism, a condition responsive means for operating said switching mechanism, spring means acting in opposition to said condition responsive means, an adjustable lost motion connection between said condition responsive means and said switching mechanism, means for adjusting the lost motion connection for varying the differential of operation of the condition responsive switch, and means for compensating the increased retarding effect of the spring means.

2. A condition responsive switch comprising, a switching mechanism, a condition responsive means for operating said switching mechanism, spring means acting in opposition to said condition responsive means, an adjustable lost motion connection between said condition responsive means and said switching mechanism, means for adjusting the lost motion connection for varying the differential of operation of the condition responsive switch, and second spring means for compensating the increased retarding effect of the first spring means.

3. In a device of the character described comprising in combination, a lever, one end of said lever being free to move between limits, control means operatively associated with the other end of said lever, a resilient condition responsive device for first moving said one end of said lever to one of its limits and then moving said other end to actuate said control means, and means

to compensate the spring rate of said resilient condition responsive device.

4. In a device of the character described comprising in combination, a first lever, one end of 5 said first lever being free to move between limits, a second lever pivoted for rotation, switch means operated by said second lever, the other end of said first lever being pivoted to said second lever, a resilient condition responsive device for first 10 moving the free end of said first lever to one of its limits and then moving said other end to rotate said second lever and actuate said switch, means to compensate the spring rate of said resilient condition responsive device, and means 15 for individually adjusting each of said limits.

5. In a device of the character described comprising in combination, a first lever, one end of 20 said lever being free to move between limits, a second lever pivoted for rotation, the other end of said first lever being connected to said second lever, a third lever pivoted for rotation, a link pivotally connecting said second and third levers, a movable contact carried by said third lever, a stationary contact, and a resilient condition 25 responsive device for first moving the free end of said first lever to one of its limits and then moving the other end of said first lever causing rotation of said second lever and hence said third lever through said link, said link being in substantial 30 alignment with the pivot for said second lever when said contacts are in closed position.

6. In a device of the character described comprising in combination, a first lever, one end of 35 said lever being free to move between limits, a second lever pivoted for rotation, the other end of said first lever being connected to said second lever, a third lever pivoted for rotation, a link connecting said second and third levers, a movable contact carried by said third lever, a stationary contact, a resilient condition responsive 40 device for first moving the free end of said first lever to one of its limits and then moving the other end of said first lever causing rotation of said second lever and hence said third lever through said link, said link being in substantial 45 alignment with the pivot for said second lever when said contacts are in closed position, means for varying the distance between said limits, and means for compensating the spring rate of 50 said resilient condition responsive device.

7. In a device of the character described comprising in combination, a first lever, one end of 55 said lever being free to move between limits, a second lever pivoted for rotation, the other end of said first lever being connected to said second lever, a third lever pivoted for rotation, a link connecting said second and third levers, a movable contact carried by said third lever, a stationary contact, a resilient condition responsive 60 device for first moving the free end of said first lever to one of its limits and then moving the other end of said first lever causing rotation of said second lever and hence said third lever through said link, said link being in substantial 65 alignment with the pivot for said second lever when said contacts are in closed position, and means for compensating the spring rate of the resilient condition responsive device, said means comprising a spring operatively connected to said third lever, said spring having no effect on said first lever when said link is aligned with the pivot for said second lever and exerting a constantly 70 increasing force on said lever as said link is moved out of alignment with said pivot.

8. In a device of the character described comprising in combination, a first lever, one end of 5 said lever being free to move between limits, a second lever pivoted for rotation, the other end of said first lever being connected to said second lever, a third lever pivoted for rotation, a link connecting said second and third levers, a movable contact carried by said third lever, a stationary contact, a resilient condition responsive device for first moving the free end of said first 10 lever to one of its limits and then moving the other end of said first lever causing rotation of said second lever and hence said third lever through said link, said link being in substantial alignment with the pivot for said second lever when said contacts are in closed position, means for compensating the spring rate of the resilient condition responsive device, said means comprising a spring operatively connected to said third lever, said spring having no effect on said first lever when said link is aligned with the pivot for said second lever and exerting a constantly increasing force on said lever as said link is moved out of alignment with said pivot, and means for individually adjusting said limits. 15

9. In a device of the character described comprising in combination, a first lever, one end of 20 said lever being free to move between limits, a second lever pivoted for rotation, the other end of said first lever being connected to said second lever, a third lever pivoted for rotation, a link connecting said second and third levers, a movable contact carried by said third lever, a stationary contact, and a resilient condition 25 responsive device for first moving the free end of said first lever to one of its limits and then moving the other end of said first lever causing rotation of said second lever and hence said third lever through said link, said link being in substantial alignment with the pivot for said second lever when said contacts are in closed position, spring 30 means for opposing movement of said condition responsive device, and means for compensating the spring rate of said spring means and said condition responsive device. 35

10. A condition responsive switch comprising, a switching mechanism, a condition responsive means for operating said switching mechanism, spring means acting in opposition to said condition responsive means, an adjustable lost motion connection between said condition responsive means and said switching mechanism, means for adjusting the lost motion connection for varying the differential of operation of the condition responsive switch, means for compensating the change in opposing effect of the spring means, and means for adjusting the spring means for adjusting the setting of the condition responsive switch. 45

11. A condition responsive switch comprising, 60 a switching mechanism, a condition responsive means for operating said switching mechanism, spring means acting in opposition to said condition responsive means, an adjustable lost motion connection between said condition responsive 65 means and said switching mechanism, means for adjusting the lost motion connection for varying the differential of operation of the condition responsive switch, second spring means for compensating the change in opposing effect of the 70 first spring means, and means for adjusting the first spring means for adjusting the setting of the condition responsive switch.
